CLAIM

The ornamental design beard trimmer, as shown and described.

DESCRIPTION

Figure 7.1 is a perspective view of a beard trimmer showing our new design;

Figure 7.2 is a rear view thereof;

Figure 7.3 is a bottom view thereof;

Figure 7.4 is a front elevational view thereof;

Figure 7.5 is a left side elevational view; the right elevational view being a mirror image thereof; and

Figure 7.6 is a top plan view thereof.
